UNITED STATES PATENT OFFICE.

ALEXANDER MORRISON BOURKE, OF LONDON, ENGLAND.

CONSTRUCTION OF SHIPS, TANKS, AND THE LIKE.

1,390,013.

Specification of Letters Patent. Patented Sept. 6, 1921.

Application filed October 4, 1920. Serial No. 414,644.

To all whom it may concern:

Be it known that I, ALEXANDER MORRISON BOURKE, a subject of the King of Great Britain, residing at 404-405 Bank Chambers, 5 Southampton Buildings, Holborn, London W. C., England, have invented certain new and useful Improvements in and Relating to the Construction of Ships, Tanks, and the like, (for which I have filed applications in 10 England, June 4, 1919, Patent No. 141,229, and Jan. 19, 1920, Patent No. 160,615,) of which the following is a specification.

This invention relates to the construction of ships, tanks, and the like, and the advantages I seek to obtain thereby comprise the following:—greatly reduced employment of costly scaffolding, staging and moldings and a consequent reduction in the cost of production, that all the components may be 20 prepared in the shops in readiness to assemble direct in their final positions, the entire structure when finished being practically integral, great strength is thereby obtained.

I will now describe a preferred embodiment of the improvements comprising my present invention with the aid of the accompanying diagrammatic drawings throughout which like reference letters denote like parts and which drawings are deemed to form 30 part of this specification and are to be read therewith as descriptive only.

Referring to the said diagrammatic drawings Figure 1 is a sectional plan of the cut water or of the stern post showing the 35 method of attaching the plating thereto. Fig. 2 is a sectional plan of one rib showing the junction of plates thereto, Fig. 3 shows the longitudinal seams of the plating. Fig. 4 is a longitudinal elevation of a ship, a portion 40 of the starboard side being broken away to show the ribs and plating of the port side in position.

Fig. 5 is an elevation of a ship showing sundry starboard ribs in position with one 45 of the outside plates in course of being slid down into its final position above the bilge. Fig. 6 is a perspective plan of a portion of the ship's side showing plates in position and the method of fixing the beams, the ribs being omitted for clearer demonstration.

Fig. 7 is a midship section of ship showing one complete rib. Fig. 8 shows a method of joining the component lengths of a rib. Fig. 9 shows an alternative method of joining the 50 component lengths of a rib. Fig. 10 is an enlarged longitudinal section of the keel

showing the rib in position. Fig. 11 shows the method of forming a double skin. Fig. 12 shows a method of joining up skin plates by pressure and Fig. 13 shows the said joint 60 after the application of pressure.

Now the generic idea of my present invention consists in hooking or dovetailing together all the component members, the following description referring to the construction of a ship, although it obviously applies to the construction of other structures.

All the main components such as the keel, keelson, stem and stern posts, ribs, and plating having been bent, molded, or otherwise 70 formed or prepared in the workshops, according to the lines of the ship shown in the working drawings, and then numbered, are brought to the slip. The stem (cutwater) stern post and ribs, are erected upon the keel 75 the plates and beams are then lowered or slid where practicable into their final positions. The structure is welded by thermit or other suitable processes at all joints, such welding being effected as convenient during the assembly of the components.

The plating or plates *a* are bent inwardly at their ends thus forming hook *b* which hooks engage corresponding recesses in the stem or stern posts *c* as shown in Fig. 1. 85

The ribs *d* are likewise bent inwardly on each side thus forming hooks *e* which are engaged by the hooks *b* of the plates *a* as shown in Fig. 2. In order to form a rigid junction between the longitudinal edges of 90 the plates *a* the said plates are provided with V-shaped projections or edges which engage V-shaped grooves formed in the edges of the butting plates. These edges in course of assembling may be kept slightly apart by the 95 insertion upon either side of the junction of a small distance piece suitable for absorption in or during the welding process. The beams which may be of any suitable section and construction according to requirements are 100 provided with suitable ends which are furnished with dove tail jaws *h* of suitable dimensions for sliding down over and gripping the ribs *d* as shown in Fig. 6.

At certain stages in the process of assembling the components, hydraulic stays or rams may with advantage be employed to form or to preserve the correct lines of the structure.

It has been found in practice that certain 110 ribs, especially those which at certain portions are curved, for example to form the

bilge of the ship, are preferably built up in convenient lengths as the component parts of the ship are assembled. Thus the rib from the keelson to the bilge may be practically straight and therefore the floor skin plates are easily slid thereon into position, but the next length of rib which carries the bilge skin plates is curved, the bilge skin plates being similarly curved so that they 5 may be slid in or hooked upon such curved length of rib after the bent length of the rib d has been joined either as illustrated in Fig. 8 where the joint is formed by a cover plate d' , or as illustrated in Fig. 9 where 10 the junction is effected by means of a step joint or in any other suitable manner. The ribs d which carry the floor skin plates are recessed transversely in the keel d^2 as shown in Figs. 7 and 10. The keel may be solid or 15 of plate bent to any suitable cross section. The keelson d^3 is applied longitudinally over and resting upon the keel d^2 and also the flat portion of the ribs d which are let in flush with the upper surface of the keel d^2 20 but the ribs may be attached to the keel in any other suitable manner.

In some cases the vessel or tank requires a double skin as depicted in Fig. 11. In this case the outer skin plates a are hooked on 30 to the ribs d as already described but the inner skin is formed by skin plates l provided with bent edges l' which butt against the outer surface of the hooked portions e of the ribs d . As an alternative method of 35 forming the inner skin, I employ inner skin plates m as shown also in Fig. 11 such skin plates being provided with bifurcated edges n which engage the outer angular surfaces of the ribs d it being understood that all 40 joints are welded as the erection of the vessel proceeds.

An alternative method of forming vertical joints which are also eminently suitable for tanks, pipes and like constructions, especially where such joints are straight, is 45 shown in section in Fig. 12. In this case the skin plates a are provided with hook shaped edges b which hook into the interior of the hook shaped edges e of the rib d . A T shaped member o having a bifurcated stem p intervenes the entire length between the 50 angular edges b of the skin plates a . The base of the rib d is preferably angular in cross section. The joint is subjected to pressure which causes it to assume the form as 55 shown in section in Fig. 13.

Claims.

1. In a sheet metal structure for ships, the combination of stem and stern posts having inclined recesses formed therein, plates having hook-shaped ends, one end of each end plate of the structure being adapted to engage an inclined recess of one of said posts, and ribs having hook-shaped ends for engaging the adjacent hook-shaped ends of intermediate plates whereby said posts, plates and ribs may be readily formed into a unitary structure by sliding said inclined ends and recess into interlocking engagement. 60

2. In a sheet metal structure for ships, the combination of stem and stern posts having inclined recesses formed therein, plates having hook-shaped ends, one end of each plate of the structure being adapted to engage an inclined recess of one of said posts, said plates being formed with a groove and the next adjacent plate having a projection adapted to fit in said groove, and ribs having hook-shaped ends for engaging the adjacent hook-shaped ends of intermediate plates whereby said posts, plates and ribs may be readily formed into a unitary structure. 70

3. In a sheet metal structure the combination of superposed plates having hook-shaped ends adapted to be placed in juxtaposition, a rib provided with hook-shaped ends for engaging the hook-shaped ends of adjacent plates and a beam having dovetail jaws adapted to engage the hook shaped ends 85 of said ribs with a sliding fit. 80

4. In a sheet metal structure, a double wall comprising outer plates having bent-over ends extending inwardly, ribs having converging ends adapted to engage the diverging ends of adjacent plates, and inner plates having inclined ends adapted to be inserted between adjacent ribs and engage the inclined ends thereof. 95

5. In a sheet metal structure, the combination of plates having inclined ends adapted to be disposed in juxtaposition, a T -shaped member having a bifurcated stem inserted between said plates and engaging one side of the inclined ends thereof, and a rib 100 having hook shaped ends for engaging the other side of said inclined ends. 105

In testimony whereof I have hereunto set my hand in presence of subscribing witness.

ALEXANDER MORRISON BOURKE.

Witness:

CHARLES SEPTIMUS BERTHON.
